United States Patent Office

Des. 181,030

Patented Sept. 17, 1957

181,030

RANGE LIGHT HOUSING

Lawrence H. Wilson, Detroit, Mich., assignor to Midwest
Manufacturing Corporation, Galesburg, Ill.

Application April 9, 1956, Serial No. 40,966

Term of patent 14 years

(Cl. D81—25)

Fig 1

1
Fig

Fig. 1 is a perspective view of a range light housing embodying my new design; and

Fig. 2 is a side elevational view thereof.

I claim:

The ornamental design for a range light housing, as shown.

References Cited in the file of this patent

UNITED STATES PATENTS

D. 157,705 Sandin ----- Mar. 14, 1950